UNITED STATES PATENT OFFICE.

OSCAR P. NYSTROM, OF HOLLAND, MICHIGAN, ASSIGNOR TO HOLLAND FURNACE COMPANY, OF HOLLAND, MICHIGAN, A CORPORATION OF MICHIGAN.

FURNACE HUMIDIFIER.

Application filed July 21, 1924. Serial No. 727,136.

To all whom it may concern:

Be it known that I, OSCAR P. NYSTROM, a citizen of the United States of America, residing at Holland, in the county of Ottawa and State of Michigan, have invented certain new and useful Improvements in Furnace Humidifiers; and I do hereby declare the following to be a full, clear, and exact description of the invention, such as will enable others skilled in the art to which it appertains to make and use the same.

This invention relates to furnaces and is especially directed to a novel construction of humidifier for the evaporation of water in the air heating space enclosed between the outer casing and the fire pot, combustion chamber and radiator of the furnace. It is a primary object and purpose of my invention to provide a humidifier in which a large evaporating surface is furnished and in which a continuous supply of water to the humidifier construction is provided so that the same never becomes dry. A further object of the invention is to provide a drain for excess of water supplied to the humidifier that such excess may be carried and delivered to the ash pit, dampening the ashes and thereby eliminating dust, and at the same time supplying a certain amount of moisture in the air which goes to the burning fuel, this being a desirable feature in furnaces. Further, it is an object and purpose of the invention to construct the water holding parts of the humidifier as an integral portion of the ash pit casting with substantially no increase in the cost of manufacture of such casting.

The construction by means of which these results and others not at present specifically stated are attained is shown in the accompanying drawings in which,

Fig. 1 is a central vertical section, from front to rear, through a furnace equipped with my invention.

Fig. 1¹ is a fragmentary enlarged detail in vertical section of the water holding part of the humidifier construction.

Fig. 2 is a horizontal section taken substantially on the plane of line 2—2 of Fig. 1.

Fig. 3 is a fragmentary front elevation of the furnace equipped with the invention and showing the means of water supply therefor, and

Fig. 4 is a fragmentary enlarged vertical section through the front of the furnace

and through the trough or spout which carries the water to the water holding portion of the humidifier construction.

Fig. 5 is a vertical elevation partly in section of a furnace showing modified arrangement of the humidifier embodying this invention and,

Fig. 6 is a sectional plan with parts broken away from the line 6—6 of Fig. 5.

Like reference characters refer to like parts in the different figures of the drawings.

As shown in Fig. 1, the furnace includes the usual ash pit 1 a fire pot including two superimposed sections 2 and 3 located above the ash pit and with a grate 2^a between the fire pot and ash pit, a combustion chamber 4 located above the section 3, and a radiator dome 5 and a radiator 6 at the upper end of the combustion chamber 4 all enclosed by a sheet metal casing 7 of the usual construction which is spaced from the inner fuel burning member of the furnace and has hot air pipes 8 at its upper end to carry heated air to the various rooms to which hot air is to be supplied by the furnace. At the front the casing is cut away and replaced by a casting 7^a. The combustion chamber casting 4 has a forwardly extending inlet 9 leading to one of the front castings 7^a in which a door 10 is mounted which may be opened for the passage of fuel to the fire pot. The ash pit has a bottom 11 and is also formed with integral forwardly extending sides 12 at the front which are spaced apart and extend to the lower casting 7 in which the usual door 13 is mounted carrying the usual draft member, the door being opened when desired for the removal of ashes.

The construction so far described is old and well known. At the upper side and at the front of the ash pit construction between the forwardly extending sides 12 a top member is integrally formed including a horizontal section 14 at the front which is then extended downwardly and to the rear at an incline as indicated at 15 with two spaced apart upper extending sides 16 cast integral with the top member, as shown, and with transverse or cross ribs 17, 18 and 19 located between the sides 16 whereby three compartments are made adapted to hold water. The cross rib 17 at its upper edge is in substantially the same plane with the upper

side of the part 14 and is in a higher plane than the upper edge of the rib 18. Directly back of the cross rib 18 an opening 20 is made through the part 15 and on the under side thereof a downwardly and inwardly inclined guide rib 21 is cast, extending from this opening 20 downwardly and inwardly to the rear along which water passing through the opening 20 may naturally pass until it reaches the lower point thereof and drops into the ash pit onto the ashes.

It will be noted that three shallow water holding compartments are thus made and it is designed that water shall be received in the compartment in front of the rib 17 until it is full, thence flow over this rib into the next compartment and when it is full flow over the rib 18 into the compartment 20 nearest the fire pot. It is only when the water in the last compartment has reached the level of the opening 20 that any excess is conducted down the guide 21 to drop into the ash pit. A very large evaporating surface is made and a large quantity of water vapor is given off with a humidifier construction made as described.

A trough or spout 22 passes through an opening in the lower front casting 7 at its inner end being located directly above the water holding compartment in front of the cross rib 17. The hot water coil for the furnace is provided with a supply pipe 23 which connects with the coil 24 while an outlet pipe 25 connects with the coil in the usual manner. In the supply pipe 23 a T 26 is interposed from which a pipe 27 of small diameter depends, at its lower end being equipped with a pet-cock 28 with a valve which may be manually operated through handle 29 shown. This pet-cock is located directly over the outer end of the trough or spout 22 and water drops into the trough in greater or less amount according to the degree that the valve is opened. This, after a little experiment and trial, may be gaged so that the proper amount of water will be furnished.

It is not necessary that the water to supply a humidifier be taken from the hot water coil supply pipe. It may be obtained from any source. It is almost universal practice to provide a hot water coil with supply pipe in the position described and it is very convenient to obtain water for the humidifier from this location.

By using this type of humidifier the water pan which has previously been commonly used is omitted and the opening usually provided for it is covered by a removable plate 30 removal of which permits inspection or cleaning of the humidifier.

The construction illustrated in Figs. 5 and 6 shows the possibility of locating the humidifier in other positions than upon the

top of the ash pit section, such for example as upon the top of the feed door section 9. This construction may be made almost identical with the structure previously described, having ribs 31, 32 and 33. The water is admitted in front of the rib 31 and flows over this rib and also the rib 32 and passes by the end of the rib 33 from where it flows into a trough 34 which encircles the combustion chamber section of the furnace and drains through a pipe 35 into the humidifier on top of the ash pit section.

An outlet pipe 36 communicating with the upper humidifier may also be provided through which a surplus amount of water will escape and drain into troughs 37 and 38 which surround the furnace beneath it. The trough 37 has a drain pipe 39 leading to the trough 38 and the trough 38 has a drain pipe 40 leading to the lower humidifier.

It is not probable that all of the humidifier pans and troughs will be necessary to produce the requisite amount of moisture in any single installation and those not necessary may be eliminated.

While the invention has been described and shown as formed as an integral part of either the ash pit casting or the feed section casting it is not necessarily so made. When the humidifier is embodied in newly constructed furnaces it is expedient to make it as shown but when it is desired to apply this humidifier to furnaces already constructed it is quite possible and practical to make the device as a separate unit and lay it upon the ash pit or feed section. When the device is made separately the guide 21 may be extended through a hole cut through the top of the ash pit section.

The construction is easily manufactured, the water holding compartments being formed on the ash pit casting and with practically no addition in cost of manufacture. The hot water coil for furnaces is a regular and almost universal installation and all that is required additional is the trough or spout 22, the T 26 and the parts connected thereto extending toward the trough. The water holding compartments are full at all times, a large evaporating surface is provided and the quantity of water held in the different compartments is relatively small so that the evaporation of the water is rapid the same being quickly heated with a resultant increase in evaporation. As a rule the amount of moisture supplied with warm air furnaces is much too small but with my invention the moisture supplied to the warm air going to the rooms of the house is greatly increased, in practice at least six-fold. And at the same time an assurance is had that the water holding compartments of the humidifier shall always be full of water and

not dry as the usual water pan in a furnace is the greater portion of the time.

Another great advantage of this type of humidifier is that the bulky water pan is eliminated permitting air to circulate freely around the space formerly occupied by the water pan which adds to the efficiency and heating capacity of the furnace.

The invention is defined in the appended claims and is to be considered comprehensive of all forms of structure coming within their scope.

I claim:

1. In a furnace, an ash pit casting and a fire pot casting located above the ash pit casting, said ash pit casting at one side having outwardly extending spaced apart sides and a top disposed between the upper edges of the sides, said top including an outer horizontal section and an integral downwardly and inwardly inclined section, spaced apart sides cast with and extending upwardly from said top, and a plurality of spaced apart cross ribs cast with the inclined section of the top and with said last mentioned sides, said cross ribs, excepting the innermost cross rib having upper edges located in planes lower than the next adjacent outer cross rib, substantially as and for the purposes described.

2. A construction containing the elements in combination as defined in claim 1, said top adjacent the next to the innermost cross rib having an opening made therethrough, and a downwardly and inwardly inclined guide rib cast integral with the top on the under side thereof and extending from said opening downwardly and inwardly.

3. A construction containing the elements in combination defined in claim 1, combined with a casing and enclosing the furnace, and a water carrying trough mounted on and extending through the casing having its inner end disposed over the said top at a point in front of the front outermost cross rib, and its outer end outside of said casing.

4. A construction containing the elements in combination defined in claim 1, combined with a casing enclosing the furnace, a water carrying trough mounted on and extending through the casing and having its inner end disposed over said top at a point in front of the front outermost cross rib, and its outer end outside of the casing, a water carrying pipe located over the front end of the trough, and a manually operable valve secured to the pipe for controlling the passage of water therefrom to the trough.

5. In a furnace, an ash pit casting and a fire pot casting located above the same, a casing enclosing the said castings, and a water holding device located directly in front of the fire pot and integrally formed with said ash pit casting comprising a downwardly and inwardly inclined bottom, spaced apart upwardly projecting sides, and a plu-

rality of spaced apart cross ribs extending between the sides, said cross ribs, excepting the innermost having their upper edges located in planes lower than next adjacent front cross rib, substantially as described.

6. In a furnace, an enclosed ash pit, a fire pot located above the ash pit, and a combustion chamber and radiator located in superimposed relation over the fire pot, a water coil extending into the combustion chamber from outside of the furnace, a water holding device located directly in front of the fire pot, a trough, a casing surrounding the ash pit, fire pot, combustion chamber and radiator, said trough extending therethrough, and means for supplying water continuously from the water coil to said trough for transference thereby to the water holding device.

7. In a furnace, including an ash pit having a forwardly projecting portion, fire pot, combustion chamber and radiator with an enclosing casing around the same, a water holding receptacle located directly above said forwardly projecting portion of the ash pit and having a downwardly and inwardly inclined bottom, sides, and cross ribs dividing the receptacle into compartments located in different horizontal planes, the cross ribs being of a height that water flows over the same from a higher to the next lower compartment when full, said lowermost compartment being formed with a drain opening at its highest point in its bottom, and means to continuously supply a predetermined amount of water to the highest compartment of the receptacle.

8. A furnace ash pit comprising a casting having substantially vertical walls continuously around the ash pit except at one side thereof, said walls being extended outwardly in spaced apart parallel vertical relation, a top disposed between the upper edges of said outwardly extended portions of said walls and including a section extending downwardly and inwardly at an angle to the horizontal, spaced apart upwardly projecting sides cast integral with said top, and a plurality of spaced apart cross ribs disposed between said last mentioned sides, said cross ribs, excepting the innermost rib having upper edges located in planes lower than the edge of the next adjacent outer cross rib.

9. A furnace ash pit comprising a casting having substantially vertical walls continuously around the ash pit except at one side thereof, said walls being extended outwardly in spaced apart parallel vertical relation at said side, a top disposed between the upper edges of said outwardly extending portions of said walls and including a section extending downwardly and inwardly at an angle to the horizontal, spaced apart upwardly projecting sides cast integrally with

said top, and a plurality of spaced apart cross ribs disposed between said last mentioned sides, said cross ribs, except the innermost rib, having upper edges located in planes lower than the edge of the next adjacent outer cross rib, and said bottom having an opening therethrough closely adjacent the next to the innermost cross rib and between the same and the innermost cross rib, substantially as and for the purposes described.

10. A furnace humidifier comprising a receptacle located in an inclined position within the jacket of a furnace, ribs extending upwardly from the bottom of the receptacle, means for supplying water to the receptacle above the uppermost rib and means for draining water from the receptacle near its lower side and for conveying said water to the ash pit of the furnace. 15
20

In testimony whereof I affix my signature.
OSCAR P. NYSTROM.
